US00D431051S

United States Patent [19]

Goto

[11] Patent Number: Des. 431,051
 [45] Date of Patent: ** Sep. 19, 2000

[54] **CONTROLLER FOR VIDEO GAME MACHINE**

[75] Inventor: **Tetyu Goto**, Tokyo, Japan

[73] Assignee: **Sony Corporation**, Japan

[**] Term: **14 Years**

[21] Appl. No.: **29/106,853**

[22] Filed: **Jun. 24, 1999**

Related U.S. Application Data

[60] Division of application No. 29/078,240, Oct. 22, 1997, Pat. No. Des. 417,664, which is a continuation-in-part of application No. 29/069,891, Apr. 2, 1997, Pat. No. Des. 398,032, which is a continuation-in-part of application No. 29/042,706, Jun. 16, 1995, Pat. No. Des. 382,603, which is a continuation-in-part of application No. 29/030,017, Oct. 3, 1994, abandoned.

CLAIM

The ornamental design for a controller for video game machine, as shown and described.

DESCRIPTION

FIG. 1 is a perspective view of a controller for video game machine showing my new design;
FIG. 2 is a top plan view thereof;

FIG. 3 is a front elevational view thereof;
FIG. 4 is a right side elevational view thereof; and,
FIG. 5 is a bottom plan view thereof.
Left and rear elevational views thereof are not part of claimed design.

The body portions shown in broken lines are for illustrative purposes only and form no part of claimed design.
